UNITED STATES PATENT OFFICE.

THOMAS B. LAYCOCK, OF WASHINGTON, INDIANA.

SPRING BED-BOTTOM.

SPECIFICATION forming part of Letters Patent No. 254,663, dated March 7, 1882.

Application filed October 28, 1881. (No model.)

To all whom it may concern:

Be it known that I, THOMAS B. LAYCOCK, a citizen of the United States, residing at Washington, in the county of Daviess and State of Indiana, have invented certain new and useful Improvements in Spring Bed-Bottoms, of which the following is a specification, reference being had therein to the accompanying drawings, in which—

10 Figure 1 is an inverted view of my improved bed-spring. Fig. 2 is a side view thereof; and Fig. 3 is a plan view, showing a series of these springs applied for use to different widths of slats. Fig. 4 is a modification. Fig. 5 is a 15 detailed plan view, and Fig. 6 is a detailed side elevation, of my invention.

This invention has relation to an improvement in bed-springs, its object being to render it capable of adaptation to slats either of 20 different widths or placed different distances apart; and it consists of two upright springs with the wire connecting together their upper ends formed with two loops formed each in part by a common wire connecting the two together, and in connecting the vertical springs 25 together at bottom in pairs by means of horizontal spiral springs, substantially as herein-after more fully set forth and claimed.

In carrying out my invention I employ two 30 upright (preferably coiled) springs, A A, with their connecting-wire B, commencing at one side of the upper end of one spring and carried toward the other spring, thence returned or recurred toward the spring it started from, 35 forming a loop, b, and again carried toward but uniting with the opposite side of the upper end of the other spring, forming a second loop, b', as clearly seen in Figs. 1 and 3. This construction will permit of the drawing apart 40 or bringing closer together of the springs by which they can be adjusted to slats of differ-

ent width or placed different distances apart, as illustrated in Fig. 3, while serving at the same time to strengthen and prevent the caving 45 of the springs.

In order to fit very wide slats, and where the distance between them is great, the vertical springs may be readily adjusted thereto by turning the spirals half round and fastening them to the slats in such manner as to clasp 50 the same from the inner part of the slat outwardly.

The lower ends of the springs which terminate underneath the slats in hooks or eyes c, as clearly seen in Figs. 1 and 2, are connected together by a spring, C, the ends of 55 which are provided with eyes or hooks d to connect them to the said ends of the spring A.

The obvious purpose of the spring C is to accommodate the varying distances the springs 60 A are placed apart in connecting their lower ends together. In lieu of the spring C, the lower ends of the springs A may be connected together, as at e, Fig. 4. To avoid creaking, the springs may be fitted with rubber tubing 65 at such points thereof as may be essential.

I claim and desire to secure by Letters Patent—

The bed-spring consisting of the upright springs A, with their upper ends connected 70 together to enable the varying of the distance between them, and their lower ends provided with hooks or eyes, combined with the spring C, connected to the lower ends of the springs A, substantially as and for the purpose described. 75

In testimony whereof I affix my signature in presence of two witnesses.

THOS. B. LAYCOCK.

Witnesses:

GEO. R. HERRICK,
JAS. A. BAXTER.
